Primary Examiner — Karen S Acker(74) Attorney, Agent, or Firm — Dunlap Bennett & Ludwig PLLC(57) CLAIM

The ornamental design for a textile with camouflage pattern, as shown and described.

DESCRIPTION

The sole FIGURE is an elevational view of a flat textile with camouflage pattern, showing my new design.

The broken lines depict environmental subject matter that forms no part of the claimed design.

All areas and broken lines that are adjacent to the shaded features and unshaded features surrounded by solid lines are portions of the textile with camouflage pattern that form no part of the claimed design.
